UNITED STATES PATENT OFFICE.

JOHN P. EUSTIS, OF NEWARK, NEW JERSEY.

DESIGN FOR TOILET WARE OR VESSEL.

SPECIFICATION forming part of Design No. 14,439, dated November 27, 1883.

Application filed September 26, 1883. Term of patent 7 years.

To all whom it may concern:

Be it known that I, JOHN P. EUSTIS, a citizen of the United States, residing at Newark, in the county of Essex and State of New Jersey, have invented and produced a new and original Design for Toilet Ware or Vessels, such as Slop-Jars and Water-Carriers, of which the following is a specification, reference being had to the accompanying drawing, forming part thereof.

The drawing shows my design applied to a slop-jar, the drawing representing in the same figure an outside elevation, partly in a vertical section, of the jar, so as to show more clearly the outlines of my design.

The leading features of my design consist in giving to the body of the vessel the shape of a truncated cone surmounted by an inverted truncated cone, the same being combined with a convex bottom, and a continuous foot-piece which projects from and is fastened to the bottom.

The letter A designates the body of the vessel, which is composed of a truncated cone, B, surmounted by an inverted truncated cone, C, which forms the upper part of the body or top of the vessel. The body A is combined with a convex bottom, D, which extends downward from the base of the truncated cone B. To the bottom D is fastened a continuous foot-piece, E, on which the vessel is supported.

What I claim as new, and desire to secure by Letters Patent, is—

The design for toilet ware or vessels herein shown and described, the same consisting of the truncated cone B, the inverted truncated cone C, convex bottom D, and the foot-piece E.

In testimony whereof I have hereunto set my hand and seal in the presence of two subscribing witnesses.

JOHN P. EUSTIS. [L. S.]
